UNITED STATES PATENT OFFICE.

JACOB DOURSON, OF COLUMBUS, OHIO.

IMPROVED EXTENSION-TABLE.

Specification forming part of Letters Patent No. 91,099, dated June 8, 1869.

To all whom it may concern:

Be it known that I, JACOB DOURSON, of Columbus, in the county of Franklin and State of Ohio, have invented a new and useful Improvement in Fall-Leaf Extension-Tables; and I do hereby declare the following to be a full, clear, and exact description of the same, sufficient to enable others skilled in the art to which my invention appertains to make and use the same, reference being had to the accompanying drawings, forming part of this specification, in which—

Figure 1 is a longitudinal central section of Fig. 2. Fig. 2 is an inverted plan view of my table when not extended. Fig. 3 is a detail view, to be hereinafter referred to.

The present invention is an improvement on the extension-table patented to me March 16, 1869.

The object is to so arrange or combine the slides that the frame of the table can be drawn out to such an extent as to render the automatic supports unnecessary. The latter may be used, however.

The invention consists in the arrangement of the slides, as hereinafter described, so as to permit the increased extension of the frame and adapt my improvement to extension-tables of large dimensions.

My invention will be fully understood by reference to the accompanying drawings, considered in connection with the following detail description.

Similar letters of reference indicate like parts in the several figures.

In the drawings, A represents the top of the table, and B B the leaves.

CCC are the legs, of which the two on each side of the table are connected together by strips D D.

E E are blocks secured immovably to the under side of the top A, and having longitudinal grooves in both sides to receive the projections of the metallic slides i, attached to the end pieces F F of the table-frame. The slides i being fully described in my former patent, above referred to, a further specification of them is deemed unnecessary here.

In my former patent the pieces F F, which are secured to the legs C C, are arranged on the outer sides of the fixed blocks E E. In the present case, as will be seen by referring

to Fig. 2, the two pieces F at the same end of the table are so secured to the legs as to be on opposite sides of the stationary blocks E. By this arrangement the pieces F can be made twice as long as before, thus permitting the legs to be drawn apart to such a distance as to afford a sufficient support for the leaves and render the auxiliary supports unnecessary.

The metallic slides i, affixed to the ends of the stationary blocks E, project from the opposite sides thereof and move in grooves in the end pieces F, and the connection is strengthened, as before stated, by similar slides i, attached to the inner ends of the pieces F and fitting in grooves in the stationary part E.

If it be desired to employ auxiliary supports for the leaves, either two, as in my former patent, or one, as in this case, can be used for each leaf. In the present case, G G represent the auxiliary supports, which are simply wooden strips centrally pivoted to the upper sides of the parts D, and having longitudinal grooves in the upper side, which receive pins a, fixed in the top A of the table underneath. When the sides D of the frame are drawn out, the auxiliary supports are brought automatically to the position shown in red lines, Fig. 2.

My improvement may be adapted to extension-tables of large dimensions by increasing the number of slides F F, as shown in red lines, Fig. 3, and attaching the outer slides of the series to the legs of the table.

Having thus described my invention, what I claim as new, and desire to secure by Letters Patent, is—

The arrangement of the slides F F, which are connected with the table-legs on opposite sides of the blocks E, when the latter are attached to the table-top A, and are connected with the parts F F by means of the metallic slides i i, all constructed and arranged to operate substantially as described, and for the purpose specified.

To the above I have signed my name this 27th day of March, 1869.

JACOB DOURSON.
